UNITED STATES PATENT OFFICE.

GEORGE B. REABEN, OF SUMMIT, MISSISSIPPI, ASSIGNOR TO VINCENT GRAY, OF NEW ORLEANS, LOUISIANA.

AUTOMATIC HOTEL CALL-BELL.

SPECIFICATION forming part of Letters Patent No. 653,459, dated July 10, 1900.

Application filed November 1, 1899. Serial No. 735,526. (No model.)

To all whom it may concern:

Be it known that I, GEORGE B. REABEN, a citizen of the United States, residing at Summit, in the county of Pike and State of Mississippi, have invented certain new and useful Improvements in Automatic Hotel Call-Bells; and I do hereby declare the following to be a full, clear, and exact description of the invention, such as will enable others skilled in the art to which it appertains to make and use the same.

My invention relates to a new and useful improvement in hotel call-bells.

It has for its object to provide an automatic alarm through the medium of which a guest occupying any room in a hotel may be automatically called at any desired hour of the day or night and by means of which all of the guests of a hotel may be promptly notified in case of fire or other impending danger.

In the present system for calling guests the guest leaves an order at the office as to the hour he may wish to be called, and this order, together with the number of his room, is entered upon a book or register kept for that purpose. The guest is then awakened or called by an employee of the hotel or an alarm-bell is caused to ring in the room, as the result of suitable mechanical or electrical devices set in operation by the clerk at the office of the hotel. This system involves of necessity the frailty of human memory or the negligence and carelessness of an employee, and it not infrequently happens from such causes that a guest is not called at the required time, and consequently with these factors of doubt a guest is never quite at ease upon the question as to whether or not he will be promptly called.

My invention is designed to overcome all of the objections recited and to provide a means which shall be absolutely automatic and precise in its operation.

With these ends in view my invention consists of a series of wires and alarm-bells connected with each room of a hotel and concentrated at the office into a switchboard electrically connected with the ordinary annunciator system and also with a clock and a series of flexible connecting-wires, through the medium of which the alarm-bell in each

room may be sounded automatically at any desired division of the hours by the travel of one or more hands moved by an ordinary clock mechanism, all as will be hereinafter more fully explained.

In order that those skilled in the art to which my invention appertains may know how to make and use my improved automatic hotel call-bell system, I will proceed to describe the construction and operation of the same and the manner of using it, referring by letters and numerals to the accompanying drawings, in which—

Figure 1 is a diagrammatic view of my improved system or apparatus. Fig. 2 is a vertical sectional view of the switchboard, taken on the line *x x* of Fig. 6. Fig. 3 is a detail section of the clock-dial, showing the manner in which the hand contacts to establish the circuit through the various switch-bars and to the rooms. Fig. 4 is a detail elevation of one of the sundry switch-cords connecting the room-wires with the time-bars. Fig. 5 is a perspective view of one of the switch or time bars, and Fig. 6 is a front elevation of the switchboard.

Similar characters of reference indicate like parts in the several figures of the drawings.

A represents a switchboard or case in which is mounted any suitable clock mechanism with a dial *B* and a single hand *C*, although an hour and minute hand may both be employed, and the dial *B* may be formed with the usual time divisions and characters. The single hand *C* or the hour-hand, as the case may be, is provided with a suitable platinum point or teat to contact with a series of inwardly-projecting radial metallic fingers *D*, forty-eight in number and representing the quarter-hour subdivisions of the twelve hours on the dial. Each of the fingers *D* is electrically connected with a series of metallic time-bars or stiff wire rods *E*, corresponding in number with the quarter-hour subdivisions of the dial. These connections consist of wires *F*, extending from each of the fingers and formed into a cable *G*, which passes through the face of the case *A*, and terminates in a series of flexible connections *H*, with contact-hooks *I*, which are secured to the ends of the time-bars *E* by binding-screws *J*. The

hand C is placed in circuit by a wire J', which may or may not pass through a single-stroke bell K to the ordinary annunciator-battery L, the opposite pole of which connects with the 5 ordinary system of room-wires M, on which in each room is placed in circuit an alarm-bell. (Not shown.)

The room return-wires M' are each tapped by wires leading to posts N on the switch- 10 board, which are numbered to correspond with the numbers of the room.

O represents flexible switch-cords, one end of which is connected with the posts N and the opposite ends provided with spring-hooks P, 15 adapted to contact and connect with the series of time bars or rods E, as shown in Fig. 6.

Each of the switch-cords passes through a pulley Q on a weight R, which is housed in a vertical tube or casing S, and consequently 20 when the hook P is released from the time-bar the weight descends within its tube or casing S and the hook is raised up to the cord passage-way through the case A and out of the way, as shown at Fig. 6.

25 The time-bars are preferably arranged on an incline, as shown at Fig. 2, in order that the switch-cords O when connected with the lower bars will not touch those above the plane of connection.

30 On the face of the case A the subdivisions of time are indicated at the ends of the time-bars E, as clearly shown at Fig. 6.

From the construction shown and described it will be seen that any one or more of the 35 switch-cords O may be connected with any one of the time-bars and any number of guests awakened or alarmed at any one time or at various times.

At Fig. 6 I have shown four switch-levers 40 1 2 3 4, which are designed to cut in additional batteries when necessary to augment the battery-power of the ordinary annunciator-battery, and these additional batteries may be provided one for each floor of the hotel.

45 The drawings illustrate my improved system adapted for a nine-room apartment, and I will now illustrate or describe its operation.

A guest in room 1 desires to be awakened at twelve o'clock and a guest in room 6 desires to be awakened at quarter after four o'clock. The switch-cord connecting room-wire of room 1 is drawn down and hooked onto the time-bar indicated by the number 12 at the right-hand end, and the switch-cord leading from room-wire of room 6 is drawn and hooked onto the time-bar marked 50 15, just below the mark or indicator 4. The wire-circuits to rooms 1 and 6 will then be established as follows: starting from the hand 55 C by the wire J', through the office-bell K to the annunciator-battery L, thence up the room-wire to the alarm-bell in rooms 1 and 6, thence down the return-wires and through their connections to the posts 1 and 6 on 60 the switchboard or case A, thence through the switch-cords O to the time-bars, with which

the hooks P are in connection, thence through said time-bars to the connections H, and through the cable to the radial fingers opposite the time-divisions "12" and "4.15" on 70 the dial. As the hand C travels in its circuit of time through the medium of the clock mechanism the point contacts with the radial arm 12, and as it continues its movement it subsequently contacts with the radial arm 75 next after the one numbered 4, and at each contact it establishes a circuit from the hand C through the bell K, (which notifies the clerk that an alarm is being sounded,) and thence to the room of the guest, ringing the alarm, 80 and back to the battery. When the bell K rings and the clerk's attention has been attracted and the guest has arisen and pushed his call-button, the annunciator will indicate that the alarm has been effective, and he then 85 releases the hook P from the time-bar and the weight R draws the hook up to its normal position. As soon as the hook has been removed from the time-bar the room in circuit with such time-bar is cut out and the alarm- 90 bell in said room ceases to ring.

It will be seen that in cases of danger, such as fire, all of the switch-cords may be connected with any one or more of the time-bars E, and a general alarm may be sounded by 95 moving the hand C by hand in an obvious manner. If the guest should not awaken during the time the hand C is in contact with the radial finger of the dial, the hand may be returned to again make contact and establish the circuit, and if no response is then received through the annunciator a messenger is sent to the room to see what the trouble may be. In practice I arrange the series of 100 time-bars about a quarter of an inch in advance of each other progressively and find that such distance is sufficient to prevent the switch-cords from contacting with the time-bars above the connections. Where a large 105 number of rooms are required to be connected with the switchboard, the weight tubes or cases S may be arranged in a bank similar to ordinary organ-pipes.

Many changes may be made in the details of construction and in the system of wiring and 110 battery service without departing from the spirit of my invention, the gist of which consists in automatically sounding an alarm in any one or more rooms at any desired hour by establishing a circuit through the medium of 115 clock mechanism, as hereinbefore explained.

What I claim as new, and desire to secure by Letters Patent, is—

1. In a device of the character described, a switchboard provided with a number of binding-posts, a series of switch-cords connected at one end to the binding-posts, engaging means on the other ends of the switch-cords, and a series of bars arranged on an incline and adapted to be engaged by the engaging 120 means, substantially as and for the purpose set forth.

2. In a device of the character described, a switchboard provided with a number of binding-posts, a series of switch-cords connected at one end to the binding-posts, metallic hooks on the other end of the switch-cords, a series of parallel bars arranged on an incline and adapted to be engaged by the hooks, a timing contact device, and connections between the contacts of said device and the parallel bars, substantially as and for the purpose set forth.

3. In a device of the character described, a switchboard provided with a number of binding-posts, flexible switch-cords connected thereto at one end, metallic hooks on the other ends of the switch-cords, weights suspended by the switch-cords, a series of bars arranged on an incline and adapted to be engaged by the hooks, binding-screws mounted on the bars, a timing contact device, and connections between the contacts of said device

and the binding-screws, substantially as and for the purpose set forth.

4. In combination with an electrical annunciator-circuit leading from several rooms or apartments, a number of binding-posts each connected with one of the wires of said annunciator-circuit, flexible switch-cords also connected with the binding-posts at one of their ends, hooks on their other ends, a series of parallel bars arranged on an incline and adapted to be engaged by the hooks, a timing contact device, and connections between the contacts of said device and the bars, substantially as and for the purpose set forth. 35

In testimony whereof I affix my signature in presence of two witnesses.

GEORGE B. REABEN.
